UNITED STATES PATENT OFFICE.

NICOLAUS CHARLES EMIL SCHWARTZ, OF NEW YORK, N. Y.

VAGINAL DOUCHE.

SPECIFICATION forming part of Letters Patent No. 752,361, dated February 16, 1904.

Application filed April 18, 1903. Serial No. 153,181. (No model.)

To all whom it may concern:

Be it known that I, NICOLAUS CHARLES EMIL SCHWARTZ, a citizen of the United States, and a resident of New York, in the county of New York and State of New York, have invented 5 certain new and useful Improvements in Vaginal Douches, of which the following is a specification.

My invention relates to improvements in 10 vaginal douches or syringes, and will be defined in its scope by the claims.

My invention consists of a vaginal douche or syringe so designed and constructed that a 15 small quantity of liquid may be repeatedly used without the removal of the syringe, a filter or strainer being provided whereby the liquid is strained between each time of use. I am thus enabled to produce a device which is 20 more convenient and effective and which is also capable of use in ways not possible with the usual type of syringes.

The drawing accompanying herewith shows 25 a section of a form of my invention now preferred by me.

Corresponding parts are denoted by the same reference characters.

My douche or syringe is of a type which employs a compressible bulb 1 for producing the required water-pressure. This is attached 30 by a flexible connection to the outer end of the nozzle or part which is inserted within the vagina, as by a short rubber tube 2, fitting over tips 7 and 6, carried, respectively, by the bulb and the nozzle.

The part which is inserted within the vagina 35 contains two principal members, which are combined in such a way as to form a vaginal-distender and a receiving-reservoir for the liquid. The outermost of these parts consists 40 of a central tube 3, which passes centrally through the other member and at one end is formed into the nipple 6, which receives the bulb connection, and at the other end is provided with suitable discharge-openings. This 45 forms a direct passage from the bulb to the discharge-orifices. The discharge end of this tube is closed except for such discharge-openings, which openings I prefer to make as slits 4, although other forms of orifice might be used.

I prefer this form, as it gives a thin sheet-like 50 discharge, which more effectually covers the surfaces to be washed than small round jets.

The tube 3 has a bell-shaped flange 5 near its outer end, which is threaded at 10 for the reception of the conical member 8, which acts 55 as a distender. This is provided at its large end with a flange 18, which is threaded to screw upon the flange 5 at 10. At its small end it is designed to fit tightly over the tube 3 and to be so tapered as to smoothly merge 60 into the outline of said tube, which projects but a small distance therefrom.

The conical distender 8 is provided with backflow-openings 9, through which the liquid after being discharged from the nozzle may 65 flow into the collecting-reservoir formed by said distender and the bell-shaped flange 5. The tube 3 is provided with a threaded opening within the bell, within which is screwed a short tube 12, which extends close down to 70 the inner surface of the bell at its largest part. This tube 12 contains a check-valve 14, which is adapted to permit flow into the tube 3, but to prevent flow in the other direction. It is designed that this tube 12 contain a filtering 75 or straining material 13, such that the water may pass therethrough, but any particles carried by the water will be retained. A convenient material to use is a small piece of sponge, which may be frequently renewed. 80 An air-exit opening 15 is provided leading from the side of the bell opposite to the tube 12. This should be kept open during the first discharge of the bulb 1, so that the air in the distender may be replaced by liquid. 85

Without the larger part of the distender, at the base of the flange 18, is shown a packing-ring 16, which should be of soft easily-compressible rubber or similar material. This is designed to engage the walls of the vaginal 90 opening and prevent escape of the liquid thereby. The outer surface of the distender is slightly grooved at 19 to form a retaining-seat for this packing-ring.

In using my douche or syringe it is first 95 filled by sucking the water through the discharge-openings 4. When in place, the water is discharged through these openings and

flows back and through the openings 9 into the space within the distender. During this first discharge the opening 15, which should be kept at the upper side, should be left uncovered. After the completion of the first discharge this opening may be closed by putting a finger over it. When the bulb is relaxed and permitted to expand, the openings 4 are closed by the walls or folds of the membrane lining of the vagina and the water within the distender is drawn through the tube 12, being strained at the same time by passage through the sponge 13 or whatever material is used in its stead. In this way the same liquid may be used for several applications, and thus an effect may be produced with a small amount of liquid which would otherwise require a considerable amount. At the same time the liquid may be finally removed in the syringe, which obviates the necessity for a vessel to catch the drip and the annoying features necessarily connected therewith. It is thus possible to use this syringe while recumbent in bed and under other circumstances where other types of syringe could not be conveniently employed.

Where a medicament is being used, the ability to successively apply it a number of times to the parts is a great advantage. In such use the strainer or filter prevents a reapplication to the parts of any foreign or injurious matter which is not soluble.

I provide a cap 17, which is adapted to fit closely over the outer end of the tube 3 and close the discharge-openings 4, so that while the syringe is filled it may be placed anywhere and in any position without leaking. This tube may be easily removed or put in place, and if put on immediately after use the syringe may be put down anywhere and left any length of time or until it is convenient to empty.

It is of course evident that a pump or other water-circulating device might be substituted for the bulb, although I prefer the bulb as being the simplest form of such devices.

I do not desire to be understood as limiting myself to the details of construction and arrangement as herein described and illustrated, as it is manifest that variations and modifications may be made in the features of construction and arrangement in the adaptation of the device to various conditions of use without departing from the spirit and scope of my invention and improvements. I therefore reserve the right to all such variation and modification as properly fall within the scope of my invention and the terms of the following claims.

Having thus described my invention, I claim and desire to secure by Letters Patent—

1. In a syringe, in combination, a bulb, a discharge pipe or nozzle attached to one end of said bulb, a reservoir receiving the backflow

having as a part thereof a distender extending into the vaginal and having inlet-openings, and a suction-pipe extending from the discharge-pipe to the lower part of the reservoir. 65

2. In a syringe, in combination, a bulb, a discharge-pipe, a reservoir having as a part thereof a distender surrounding said discharge-pipe and extending into the vaginal and having inlet-openings and a valved suction-pipe leading from said discharge-pipe to the lower part of the space within said distender. 70 75

3. In a syringe, in combination, a bulb, a discharge pipe or nozzle attached to said bulb, a reservoir to receive the backflow having as a part thereof a distender extending into the vaginal and having inlet-openings, a suction-pipe extending from the discharge-pipe to the lower part of the reservoir, and a strainer for said suction-pipe. 80

4. In a syringe, in combination, a bulb, a discharge-pipe, a distender surrounding said discharge-pipe, a valved suction-pipe leading from said discharge-pipe to the lower part of the space within said distender, and a strainer for said suction-pipe. 85 90

5. In a vaginal douche or syringe, in combination, a bulb or equivalent water-circulating device, a discharge-pipe leading therefrom, a reservoir receiving the outflow, a suction-pipe and strainer therefor connecting the bulb and said reservoir. 95

6. In a vaginal douche or syringe, in combination, a bulb, a discharge-pipe leading therefrom, a reservoir receiving the outflow and provided with an air-discharge opening 100 and having as a part thereof a distender extending into the vaginal and having inlet-openings, and a suction-pipe connecting said bulb and reservoir. 100

7. In a vaginal douche or syringe, in combination, a bulb, a discharge-pipe leading therefrom, a reservoir receiving the outflow and provided with an air-discharge opening, and a suction-pipe connecting said bulb and reservoir and provided with a strainer. 105 110

8. In a vaginal douche or syringe, in combination, a bulb, a discharge-pipe leading therefrom, a flange surrounding said pipe, and a conical distender having its smaller end closely surrounding said pipe and its larger 115 end secured upon said flange and inlet-holes in its side. 110

9. In a vaginal douche or syringe, in combination, a bulb, a discharge-pipe leading therefrom, a flange surrounding said pipe, and a conical distender having its smaller end closely surrounding said pipe and at its larger end having an enlargement adapted to be secured to the said flange, and a packing-ring surrounding the distender in advance of said 120 enlargement. 125

10. In a vaginal douche or syringe, in combination, a hollow conical distender having

openings in its side, a bulb and a discharge-pipe connected with the bulb and extending entirely through said distender and having jet-orifices in its inner or discharge end, and
5 a flange extending from the discharge-pipe and adapted to screw upon the large end of said distender to close it.

In testimony whereof I have signed my name in the presence of the subscribing witnesses.

NICOLAUS CHARLES EMIL SCHWARTZ.
